BOOTH & RIPLEY.

Car Seat.

No. 8,508.

Patented Nov. 11, 1851.

UNITED STATES PATENT OFFICE.

EZEKIEL BOOTH AND EZRA RIPLEY, OF TROY, NEW YORK.

IMPROVEMENT IN CAR-SEATS.

Specification forming part of Letters Patent No. **8,508**, dated November 11, 1851.

To all whom it may concern:

Be it known that we, EZEKIEL BOOTH and EZRA RIPLEY, of Troy, in the county of Rensselaer and State of New York, have invented a certain new and useful Improvement in the Mode of Reversing High-Back (or Night) Car-Seats; and we do hereby declare that the following is a full, clear, and exact description of the construction and operation of the same, reference being had to the annexed drawings, which make a part of this specification, in which—

Figure 1 is a perspective view of the seat, and Fig. 2 is a view of one arm, taken in a cross-section inside of the arm with the back in a horizontal position, as in the act of reversing from one side of the seat to the other, the same letters having reference to like parts in both figures.

Our invention consists in the arrangement of two levers A A, on which the back B is suspended and reversed from one side of the seat C to the other, which levers cross each other and are secured by pivots *a a* to the arms D D, and to the back at *b b*. When the back is in

its position for use, as in Fig. 1, one lever extends across the arm in or nearly in a horizontal position and the other inclines to a vertical position. The lever in the horizontal position rests upon a stop-pin *c* and retains the back in its proper position. Thus the center of the back is secured at any required distance above the arms, and the required height of back is obtained, so as to be reversible, and shall not necessarily extend below the seat on either side.

Having thus described the nature of our invention, what we claim as new, and desire to secure by Letters Patent, is—

The arrangement of two levers in a cross position, so as that any required height of back may be carried and reversed from and to either side of the seat and secure it firmly in its position at any required angle, substantially the same as described and represented.

EZEKIEL BOOTH.
EZRA RIPLEY.
